UNITED STATES PATENT OFFICE.

ALBERT G. CUMMINGS, OF MILLERSBURG, PENNSYLVANIA, ASSIGNOR TO
FREDERICK W. WOOD, OF BALTIMORE, MARYLAND.

HYDRAULIC PACKING DEVICE.

SPECIFICATION forming part of Letters Patent No. 718,701, dated January 20, 1903.

Application filed November 18, 1901. Serial No. 82,654. (No model.)

To all whom it may concern:

Be it known that I, ALBERT G. CUMMINGS, a citizen of the United States of America, and a resident of Millersburg, Pennsylvania, have 5 invented certain new and useful Improvements in Hydraulic Packing Devices, of which the following is a specification.

My invention relates to a hydraulic stuffing-box; and its object is to provide a stuffing-box which will pack a hydraulic joint 10 tightly and with economy of packing material, be entirely impervious to grit from both directions, and include also a lubricating-box by which lubricant is applied to the piston-rod or piston.

In the drawings, Figure 1 is a vertical section of the stuffing-box or piston-rod. Fig. 2 is a vertical transverse section through the line $\alpha\gamma$ of Fig. 1. Fig. 3 is an end view of 20 the stuffing-box, showing the box-head in full and the piston-rod in section. Fig. 4 is a view, partly in full elevation and partly in vertical section, of the device for forcing the packing forward on the gland. Fig. 5 is a 25 partially full elevation, partly vertical section of the cap which covers the lubricant-chamber. Fig. 6 is a vertical section of the stuffing-box. Fig. 7 is a vertical section of the gland. Fig. 8 is a vertical section of the 30 split-metal packing-ring. Fig. 9 is a side elevation of same. Fig. 10 is an enlarged view showing in vertical section a part of the stuffing-box and gland with the packing in 35 place and indicating the relative position of these parts in practice. Fig. 11 is a vertical section of a modified form of gland.

Referring to Fig. 1, 1 is a cylinder-head on which the stuffing-box is mounted and to which it is secured.

2 is a piston-rod or piston. It will be understood that the construction will be the same and the same in operation whether the pump consist of a piston and piston-rod or a plunger of uniform size throughout.

3 is a cylindrical flange fixed on the face of the cylinder-head and provided on opposite sides with lugs 4 4, into which are tapped bolts 5 5.

6 6 are lock-nuts which lock the bolts onto

the lugs 4 4. The bolts 5 5 are each provided 50 with collars 6^a 6^a, integral with the bolts, and the bolts are threaded on their ends to receive set-nuts 7 7.

8 is the stuffing-box, tapped into the cylinder-head and perforated through its center. It is shown in vertical section detached from the outer construction in Fig. 6. The piston-rod passes through the center of its bottom. It will be noticed that the stuffing-box is provided with inclined walls upon the 55 interior which converge at two angles toward the central aperture. The portion of the inclined wall having the smaller angle with the axis of the box is marked 9. The steeper portion of the wall, having the greater angle, 60 is marked 10.

11 is the gland shown in detail in Fig. 7. It fits snugly around the piston-rod and is recessed at its forward end to provide a seat 65 for an antifriction metal ring. It is provided on its exterior at the left-hand end with an integral collar 12 and is tapered toward its right-hand end. Near the end it is provided with a series of parallel steps or 70 grooves which encircle its exterior surface. 75

The ridges or steps between the grooves are of such a height as to correspond with the taper. The grooves are marked 13 13 and the ridges or steps 14 14. The extreme end of the gland is tapered abruptly at an angle 80 much greater than the balance of the gland and at an angle slightly greater than the angle of the inclined wall at the bottom of the stuffing-box. Surrounding the gland is a hollow cylinder 15, provided upon its interior with 85 two inwardly-projecting flanges 16 16 and upon its exterior with a square thread 17. On one side of the cylinder there is a horizontally-projecting flange 18, provided with a series of radial sockets 19 19. The cylinder 90 is shown in detail in Fig. 4. The gland 11 fits closely into the cylinder 15 and the inwardly-projecting flanges 16 16 rest upon the exterior wall of the gland. Surrounding the gland and the cylinder is a casing 20, 95 which is cylindrical in form and provided upon its exterior with two lugs 21 21, which are perforated and through which pass the

bolts 5 5. On the interior of the casing, at about its center, there is an inwardly-projecting flange 22, having a central aperture which fits upon the left-hand end of the gland, the 5 collar 12 of the gland bearing against the right-hand side of the flange 22. Upon the interior of the right-hand end of the casing there is cut a square thread-groove 23, into which meshes the thread 17 of the cylinder 15. The left-hand end of the casing 20 is threaded upon its exterior, and upon that thread is screwed a cap 24. (Shown in detail in Fig. 5.)

The casing 20 and cap 24 constitute an auxiliary stuffing-box which guards the main stuffing-box against the admission of grit from the outside. This stuffing-box may be packed with any form of packing or lubricant for the purpose of cleaning and lubricating 20 the piston-rod. I prefer to use a diaphragm surrounding the piston and dividing the auxiliary stuffing-box into two chambers, one of which may contain lubricant and the other packing.

25 25 is an antifriction-ring which is split so as to be compressible and surrounds the piston-rod and is situated in the socket 26 in the inner side of the right-hand end of the gland. Leather or other suitable packing 30 material is used for packing the joint, and it is placed around the gland in the grooves 13 13 and over the ridges or steps 14 14, covering the ring 25 and bearing upon the piston-rod. The packing is extended over the gland 35 to a point somewhat beyond the end of the stuffing-box, and the gland is then moved up on the piston-rod until the gland, covered by its packing material, makes contact with the interior of the stuffing-box. The angle of the 40 end of the gland being more abrupt than the angle of the bottom of the stuffing-box, the packing will be pinched tightly between the top of the last ridge on the end of the gland and forced forward from that point without 45 exerting any material compression upon that part of the packing which is behind it, the angle of the taper of the gland back of the top of the last ridge upon it being somewhat less than the taper of the wall of the box opposite to it.

I have found this construction 50 to be the most effective, but a different arrangement of angles will give good results. I may make the angles of the taper of the gland the same as the angles of the inclination 55 of the wall of the stuffing-box, so that the surfaces may be parallel, the only essential point being that the surfaces should be approximately parallel. The packing material, therefore, which is in front of the end of 60 the gland will be forced forward against the inclined wall of the box and down upon the piston-rod and upon the metal ring, which is split and capable of being contracted upon the piston-rod and which lies below the end 65 of the gland and is forced forward by it. The gland is moved forward by tightening the

nuts 7 7, which push forward the casing 20, the cylinder 15, and the gland 11, until the lugs 21 21 come in contact with the collars 6^a 6^a upon the bolts 5 5. When this takes 70 place, the limit of motion of the parts in their then relation has been reached and their relation must be changed. The nuts 7 7 are then loosened, and the casing 20, cylinder 15, and the gland 11 are drawn back until the flange 18 75 and the sockets 19 are drawn out of the covering-flange 3. A pin may then be inserted in one or more of the sockets 19 and the cylinder 15 screwed out of the casing 20. The packing 80 which surrounds the end of the gland having been entirely relieved of contact with the stuffing-box will be pushed forward on the gland by the cylinder 15 until it has advanced far enough beyond the end of the gland to supply a sufficient quantity of packing 85 beyond the gland to pack the joint. The nuts 7 7 are then tightened, and the gland, cylinder, and casing are carried forward together until the gland again bites against the interior of the stuffing-box, with a sufficient 90 quantity of packing material ahead of the end of the gland to make a joint. The lugs 21 21 have not yet contacted with the collars 6^a 6^a, and the nuts 7 7 are screwed up only so far as is necessary to make the joint 95 desirable; but they are tightened as the packing wears, and it becomes necessary to exert greater and greater pressure upon the packing beyond the end of the gland. By this means the packing need not be removed from 100 the gland in order to tighten it; but it may be moved forward upon the end of the gland, so as to pack the joint as often as may be required. When the cylinder 15 has been 105 screwed out of the casing 20 so far as to make contact with the end of the stuffing-box 9, then the nuts must be released and the cylinder 15 screwed back into the casing 20 and a new piece of packing inserted between the rear end of the packing already covering the 110 end of the gland and the inwardly-projecting flange 16^a of the cylinder 15, when the same operation may be repeated.

While I have described my stuffing-box as applicable to pumps and it is intended to 115 use it principally for making a packing which will resist the action of water under pressure, it is equally applicable for devices using any other fluid, such as steam or air.

Having thus described my invention, what 120 I claim as new, and desire to secure by Letters Patent, is—

1. In a stuffing-box the combination of a box, the interior wall of which is inclined toward the axis, one portion of the wall at one 125 end of the box being inclined at a small angle to the axis and the other portion of the wall at the other end of the box being inclined at a greater angle to the axis, with a gland surrounding the piston-rod which is 130 tapered at its end, at two angles, one portion being tapered at a small angle to the axis

while the taper of the extreme end is abrupt, the angle of the inclined wall of the box having the small angle being greater than the angle of the tapered portion of the gland having the small angle, and the angle of the inclined wall of the box having the greater angle being less than the angle of the tapered end of the gland, substantially as described.

5 2. In a stuffing-box the combination of a box the interior wall of which is inclined toward the axis, one portion of the wall at one end of the box being inclined at a small angle to the axis, and the other portion of the wall at the other end of the box being inclined at a greater angle to the axis, with a gland surrounding the piston-rod which is tapered at its end at two angles one portion being tapered at a small angle to the axis while the taper of the extreme end is abrupt, the surface of the said abrupt end being concave, the angle of the inclined wall of the box having the small angle, being greater than the angle of the tapered portion of the gland, having the small angle, and the angle of the inclined wall of the box having the greater angle, being less than the angle of the tapered end of the gland, substantially as described.

10 3. In a stuffing-box the combination of a box the interior wall of which is inclined toward the axis, one portion of the wall at one end of the box being inclined at a small angle to the axis, and the other portion of the wall at the other end of the box being inclined at a greater angle to the axis, with a gland surrounding the piston-rod which is tapered at its end at two angles one portion being tapered at a small angle to the axis while the taper of the extreme end is abrupt, the surface of the said abrupt end being concave, the angle of the inclined wall of the box having the small angle, being greater than the angle of the tapered portion of the gland, having the small angle, and the angle of the inclined wall of the box having the greater angle, being less than the angle of the tapered end of the gland, substantially as described.

15 4. In a stuffing-box the combination of a box the interior wall of which is inclined toward the axis, one portion of the wall at one end of the box being inclined at a small angle to the axis, and the other portion of the wall at the other end of the box being inclined at a greater angle to the axis, with a gland surrounding the piston-rod which is tapered at its end at two angles one portion being tapered at a small angle to the axis while the taper of the extreme end is abrupt, the inclined surface of the gland being provided with annular grooves and intervening ridges or steps, the angle of the inclined wall of the box having the small angle, being greater than the angle of the tapered portion of the gland, having the small angle, and the angle of the inclined wall of the box having the greater angle, being less than the angle of the tapered end of the gland, substantially as described.

20 5. In a stuffing-box the combination of a box the interior wall of which is inclined toward the axis, one portion of the wall at one end of the box being inclined at a small angle to the axis, and the other portion of the wall at the other end of the box being inclined at a greater angle to the axis, with a gland surrounding the piston-rod which is tapered at its end at two angles one portion being tapered at a small angle to the axis while the taper of the extreme end is abrupt, the angle of the inclined wall of the box having the small angle, being greater than the angle of the tapered portion of the gland, having the small angle, and the angle of the inclined wall of the box having the greater angle being less than the angle of the tapered end of the gland, and a compressible ring surrounding

the piston-rod, and located between the box and the end of the gland, substantially as described.

5 6. In a stuffing-box the combination of a box the interior wall of which is inclined toward the axis, one portion of the wall at one end of the box being inclined at a small angle to the axis, and the other portion of the wall at the other end of the box being inclined at a greater angle to the axis, with a gland surrounding the piston-rod which is tapered at its end at two angles one portion being tapered at a small angle to the axis while the taper of the extreme end is abrupt, the angle of the inclined wall of the box having the small angle, being greater than the angle of the tapered portion of the gland having the small angle, and the angle of the inclined wall of the box having the greater angle being less than the angle of the tapered end of the gland, and means for forcing the gland into the stuffing-box, substantially as described.

10 7. In a stuffing-box the combination of a box surrounding the piston-rod and secured to the cylinder-head, having its internal walls converging toward its axis, with a gland surrounding the piston-rod, and having its exterior surface tapered toward its end, packing surrounding the gland and filling the space between the box and the gland, and means for forcing the gland into the box, substantially as described.

15 8. In a stuffing-box the combination of a box surrounding the piston-rod and secured to the cylinder-head, having its internal wall converging toward its axis, with a gland surrounding the piston-rod, and having its exterior surface tapered toward its end, packing surrounding the gland and filling the space between the box and gland, means for forcing the gland into the box, and means for forcing the packing off the end of the gland, independent of the means for forcing the gland into the box.

20 9. In a stuffing-box the combination of a box having its interior wall converging toward its axis, a gland concentric with the box, and having its exterior surface tapered on the end which enters the box, packing surrounding the gland and filling the space between the box and the gland, a casing surrounding the gland, and bearing upon its rear end, and provided with means for forcing the gland into the box, and a sleeve surrounding the gland, threaded into the casing, and bearing upon the rear end of the packing, substantially as described.

25 10. In a stuffing-box the combination of a box having its interior wall converging toward its axis, a gland concentric with the box, and having its exterior surface tapered on the end which enters the box, packing surrounding the gland, and filling the space between the box and the gland, a cylindrical casing larger than the gland, having an inwardly-projecting flange at or about the center of its

interior surface, the cylinder at one end surrounding the gland, and at the other end the piston-rod, the space between the cylinder and the piston-rod being packed with cleaning and lubricating material, substantially as described.

Signed by me at Baltimore city, in the State

of Maryland, this 12th day of November, 1901.

ALBERT G. CUMMINGS.
